Primary Examiner — Cathy Anne MacCormac

(57) **CLAIM**

The ornamental design for a feline play structure, as shown and described.

DESCRIPTION

FIG. 1 is a perspective view of the invention;
 FIG. 2 is a reduced front elevation view, the right side elevation view being identical thereto;
 FIG. 3 is a rear elevation view of FIG. 2, the left side elevation view being identical thereof; and,
 FIG. 4 is a top plan view of FIG. 2.
 The bottom of the feline play structure is not shown and is not claimed.
